SHUTTLECOCK

William Charles Carlton, 14 Herbert Road,
Hornchurch, England

Filed Mar. 21, 1960, Ser. No. 59,821

Term of patent 14 years

(Cl. D34—5)

Fig. 1 is a side elevation of a shuttlecock showing my design;

Fig. 2 is a fragmentary elevation on an enlarged scale showing that portion of the shuttlecock which is enclosed within the line II of Fig. 1;

Fig. 3 is a top plan view of the shuttlecock;

Fig. 4 is a cross section on line IV-IV of Fig. 3, looking in the direction of the arrows;

Fig. 5 is a cross section on line V-V of Fig. 1, looking in the direction of the arrows.

I claim:

The ornamental design for a shuttlecock, as shown.
